WATER SLED

Anastasios J. Vasilatos, 244 Hibbard Road,
Wilmette, Ill. 60091

Filed Feb. 12, 1969, Ser. No. 15,751

Term of patent 7 years

Int. Cl. D12—06

U.S. Cl. D71—1

FIG. 1 is a perspective view of a water sled from the front and left thereof;

FIG. 2 is a right perspective view of the water sled from the right and rear thereof;

FIG. 3 is a bottom plan view;

FIG. 4 is a side elevational view.

I claim:

The ornamental design for a water sled, as shown.
